UNITED STATES PATENT OFFICE

WILLIAM D. SMITHSON AND JOSEPH L. HAIR, OF WICHITA FALLS, TEXAS; SAID SMITHSON ASSIGNOR TO O. G. STEPHENS, C. V. STEPHENS, M. D. STEPHENS, L. W. STEPHENS, AND M. L. STEPHENS, ALL OF WICHITA COUNTY, TEXAS

REEL

Application filed October 2, 1929. Serial No. 396,865.

The object of this, our present invention is the provision of a hose reel adapted primarily for use at automobile filling stations for supplying automobile radiators with water which shall be of a construction and arrangement of parts to insure economy and service. A further object is the provision of a reel for this purpose that is mounted on a suitable stand, the mount for the reel being such as to serve as a conductor of water for the hose that is wound around the reel, the said reel being turned by spring means to wind the hose thereon, means for regulating or equalizing the tension of such spring means, means for checking the movement of the reel when the hose is unwound therefrom or when the hose is wound thereonto, and means for locking the reel when the hose is wound therearound or when the hose is partly drawn therefrom.

A still further object is the provision of a device for this purpose in which the parts constituting the same may be wholly concealed and thereby protected.

The invention will be fully and comprehensively understood from a consideration of the following detailed description when read in connection with the accompanying drawings which form part of the application, with the understanding, however, that the improvement is capable of extended application and is not confined to the exact showing of the drawings nor to the precise construction described and, therefore, such changes and modifications may be made therefrom as do not affect the spirit of the invention nor exceed the scope thereof as expressed in the appended claims.

In the drawings:

Figure 1 is a side elevation of the improvement.

Figure 2 is a similar view but looking toward the opposite side thereof.

Figure 3 is an enlarged detail transverse sectional view approximately on the line 3—3 of Figure 1.

Figure 4 is a detail sectional view through a cylindrical upper portion of the stand to illustrate the manner in which the nozzle end

of the hose is guided through the box-like mouth of the stand.

Figure 5 is a detail sectional view to illustrate the hydraulic check or brake.

Figure 6 is a sectional view approximately on the line 6—6 of Figure 5.

Figure 7 is a face view of the spirally wound cone to which the flexible element for the spring is attached.

Referring now to the drawings in detail, the numeral 1 designates the vertically disposed elongated base portion of the casing and the numeral 2 designates the round upper head of the casing.

If desired both sides or faces of the head 2 may be closed, and the head is provided with an opening that communicates with the hollow base 1. The hollow base has directed therethrough and into the head 2 a water conducting pipe 3 which, of course, may have its passage valve controlled, and which, at the portion thereof arranged approximately centrally in the head 2 has connected thereto a water conducting element which we will term a nipple and which is indicated by the numeral 4. The inner flat face of this nipple is provided with a round opening that is received in an annular groove in a nut-like member 5 that is fixed on one end of a hollow shaft 6.

While we make no specific claim to the manner in which the hose is connected with the hollow shaft 6, it is to be understood that the joint therebetween is water proof. The hollow shaft 6 is fixed on the hub 7 of the reel 12. The hollow shaft is journaled through suitable bearings 9 that are fixedly secured in the head of the improvement. The hub 7 is provided with a short pipe or tube 10 that communicates with the hollow shaft 6, and to the projecting end of this tube there is fixed the inner end of the hose 11 which is wound upon itself in the bifurcated or cross sectionally U-shaped periphery of the reel 12.

Movable through a suitable opening, and guided along a flanged plate 13 in the top of the head 2 there is a spring influenced stem 14 whose outer end is provided with a head 15 and whose inner end is widened and bifurcated, as at 16. This bifurcated end is in fric-

tional contact with the peripheral edge of the reel 12 and serves as a stop to prevent the free movement of the reel, and likewise tends to hold the reel from movement when the 5 hose 11 is unwound therefrom.

The cylindrical head 2 of the casing is provided with a substantially rectangular extension 17 that surrounds an opening in one side thereof, and this opening provides the mouth 10 for the casing. The mouth 17 is normally closed by a hinged door 18, the said door being influenced to closed position through the medium of spring means 19 (Figure 1).

The nozzle end of the hose may in itself 15 provide a valve or the same may have attached thereto a hand operated valve of ordinary type. The hose is guided through a bracket 20 in what I have termed the mouth 17 of the head 2, and is likewise guided between 20 grooved rollers 21 that are journaled in the bracket. The hollow shaft 6 has a solid end.

On one of its faces there is fixed or may be 25 integrally formed with the hub 7 and the solid end of the shaft 6 which projects through the hub a spirally wound peripherally grooved drum 22. To the inner shoulder and at the widened end of the drum 22 there is fixed one end of a strong cable 23. This 30 cable is directed downwardly through the stand and has its lower end fixed to one end of a coil spring 24. The lower end of the said spring is fixed to a transverse plate or the like 25 in the lower portion of the base 1 of the stand. This construction provides an 35 important feature of the improvement, as the same equalizes the tension of the spring when the cable is brought over the different areas of the spirally wound drum when the hose is unwound from the reel or is permitted to wind 40 thereon.

The solid end of the shaft 6 has fixed thereon a pinion 26. This pinion is in mesh with internal teeth on a segment 27. The straight and non-toothed edge of the segment is pivotally secured, as at 28, to a bracket or bearing that is supported from a plate or bar 29 whose ends are fixed in the head of the stand. There is pivotally secured, as at 30, to the outer and flat face of the toothed segment 45 27 one end of a piston rod. The piston rod is received through a packing box at one end of a cylinder 31. The cylinder 31 has a closed 50 end. The closed end of the cylinder is formed with an ear extension which is pivoted, as at 32, to a bracket 33 that is fixed on the inner periphery of the head of the stand. The inner end of the piston rod carries a cup-like piston or plunger 34, and the 55 cylinder 31 is provided with a longitudinal by-pass 35 that permits of the fluid 37 in the said cylinder passing to either side of the piston or plunger 34. A valve in the nature of a bolt having a pointed end is screwed through the cylinder in a line with the groove or by-pass 35, and the outer end of this valve

has a knurled head 36. This device provides a hydraulic check or brake. When the hose is drawn out by the turning of the reel the pinion 26 acting on the segmental or semi-circular gear 27 causes the cup-shaped piston 70 34 to move toward one end of the cylinder 31 and thereby forces the fluid 37 through the port or by-pass 35 against the second end of the cylinder and against the second face of the piston 34, so that when the spring 24 rewinds the hose on the reel a resistance will be offered to the tension of the spring and thereby equalizes the tension on the hose, so that the same will wind the hose in an easy and steady manner. The bifurcated end on the spring influenced stem 14 is designed to exert a sufficient friction against the reel 12 to prevent a free turning of the said reel, but not sufficient friction to hold the reel from turning when a pull is exerted upon the hose 11 to draw the same outwardly and to permit of the reels being returned to wound position on the drum 22.

It will be noted by those skilled in the art to which the invention relates that with our improvement a hose can be readily unwound from the reel, checked by the braking element 14 so that water can be supplied to an automobile radiator or the like, released and wound by the spring 24 and checked in both its winding and unwinding actions and it is thought that further detailed description will not be required in setting forth the construction and advantages of the device.

Obviously the base 1 of the casing may be 100 provided with a doorway and may contain therein suitable heating means for heating the water conducting pipe during wintry weather.

Having described the invention, we claim: 105

1. A hose reel for the purpose set forth, including a stand having a water conducting pipe leading thereto, a shaft having a hollow portion to which the end of the pipe is connected, bearings for the shaft, a hub fixed on the shaft and having a tubular portion extending from the shaft and to which one end of a hose is designed to be connected, a reel body fixed on the hub and having a peripheral bifurcated portion to receive the wound hose therein, spring influenced stop means for normally holding the reel from turning, said stand having an outlet provided with an opening into which the nozzle end of the hose is directed, guide means for said end of the hose, a spring influenced door for closing the outlet, spring means for returning the reel to initial position when the hose is wound therefrom, and a hydraulic brake actuated by the turning of the reel for checking the same when returned by the spring means to initial position.

2. A hose reel for the purpose set forth including a stand having a water conducting pipe leading thereto, a shaft having a hol- 130

low portion to which the end of the pipe is connected, bearings for the shaft, a hub fixed on the shaft and having a tubular portion extending from the shaft and to which one 5 end of a hose is designed to be connected, a reel body fixed on the hub and having a peripheral bifurcated portion to receive the wound hose therein, spring influenced stop means for normally holding the reel from 10 turning, said stand having an outlet provided with an opening, into which the nozzle end of the hose is directed, guide means for said end of the hose, a spring influenced door for closing the outlet, spring means for re- 15 turning the reel to initial position when the hose is wound therefrom, and a hydraulic brake actuated by the turning of the reel for checking the same when returned by the spring means to initial position, and means 20 on the hub for equalizing the tension of the spring means during the unwinding of the hose. 85

3. A hose reel for the purpose set forth, including a stand having a water conducting pipe therein, a shaft having a hollow portion connected with the outlet of the pipe and revoluble in said outlet, bearings for the shaft, a hub fixed on the shaft having a tubular portion communicating with the 25 hollow shaft, and to which the end of the hose is connected, a disc-like body fixed to the hub and having a peripheral bifurcation in which the wound hose is received, a spring influenced latch carried by the stand and en- 30 gaging with the periphery of the reel, guide means for the nozzle end of the hose, a hinged door which is spring influenced to closed position for concealing the nozzle end of the hose, a spirally wound peripherally 35 grooved drum fixed on the hub, a cable fixed on the drum, a fixed coil spring to which the cable is secured, and a hydraulic brake operated by the turning of the drum in hose unwinding direction for retarding the action 40 of the spring in winding the drum. 100

4. A hose reel for the purpose set forth, including a stand having a water conducting pipe therein, a shaft having a hollow portion connected with the outlet of the pipe 45 and revoluble in said outlet, bearings for the shaft, a hub fixed on the shaft having a tubular portion communicating with the hollow shaft, and to which the end of a hose is connected, a disc-like body fixed to the hub and 50 having a peripheral bifurcation in which the wound hose is received, a spring influenced latch carried by the stand and engaging with the periphery of the reel, guide means for the nozzle end of the hose, a hinged door 55 which is spring influenced to closed position for concealing the nozzle end of the hose, a spirally wound peripherally grooved drum fixed on the hub, a cable fixed on the drum, a fixed coil spring to which the cable is se- 60 cured, a pinion on the second end of the 110

shaft, a segmental internal gear in mesh with the pinion, a pivotal support for the gear, a piston rod pivoted to the gear, a cylinder for a fluid pivotally secured in the stand, a cup-shaped plunger on the piston 70 rod received in the cylinder, said cylinder having a longitudinal bypass in one of the walls thereof and a threaded needle valve for controlling the passage of fluid through said bypass for the purpose set forth. 75

In testimony whereof we affix our signatures.
